UNITED STATES PATENT OFFICE.

IRA S. DOWNING, OF CLEVELAND, OHIO, ASSIGNOR TO WALTER P. MURPHY, OF CHICAGO, ILLINOIS.

SHEET-METAL CAR END.

1,265,065.

Specification of Letters Patent.

Patented May 7, 1918.

Application filed March 5, 1912. Serial No. 681,784.

To all whom it may concern:

Be it known that I, IRA S. DOWNING, a citizen of the United States, residing at Cleveland, in the county of Cuyahoga and 5 State of Ohio, have invented certain new and useful Improvements in Sheet-Metal Car Ends, of which the following is a specification.

My invention relates to railway cars, and 10 has for its object to provide a sheet metal end structure for railway cars having certain novel and improved features which will be hereinafter described and claimed. It has been proposed to construct the ends 15 of railway box cars of sheet metal instead of the usual timber construction and to corrugate or rib the sheet or sheets of metal employed so as to increase their capacity to withstand shocks and stresses. These proposed end structures, however, as a general rule are deficient in respect to their capacity to withstand vertical stresses. Hence they 20 cannot, for example, be relied upon to aid, to any considerable extent, in supporting the roof of the car. Thus when the corrugations run horizontally of the structure the capacity of the end to support the load of the roof is materially decreased rather than increased. My invention has for one of its 25 primary objects to provide a corrugated or ribbed sheet metal end structure in which the corrugations or strengthening and stiffening ribs are so disposed that the structure will effectually resist all of the various 30 stresses and pressures to which they may be subjected in use; and in which the corrugations or ribs, or at least some of them, are arranged specifically with the purpose of enabling the end structure to take part of 35 the roof load.

The invention has for a further object such other new and improved constructions, arrangements and devices relating to sheet metal car ends as will be described and 40 claimed.

The invention is illustrated, in certain preferred embodiments, in the accompanying drawings, wherein—

Figure 1 is an end view of a railway box 45 car illustrating one form of my invention;

Fig. 2, a vertical sectional view taken on line 2—2 of Fig. 1, looking in the direction of the arrows;

Fig. 3, a sectional plan on line 3—3 of Fig. 1;

65

Fig. 4, a detail view in elevation, of a preferred form of end door construction;

60

Fig. 5, a sectional view taken on line 5—5 of Fig. 4, looking in the direction of the arrows;

65

Fig. 6, a similar view taken on line 6—6 of Fig. 4;

65

Fig. 7, a fragmentary view, in perspective, of the end structure shown in the preceding figures;

65

Fig. 8, a view similar to Fig. 1 illustrating a modification;

70

Like characters of reference indicate like parts in the several figures of the drawings.

Referring first to Figs. 1 to 7 inclusive, the end structure is made up of two sheets of metal 25, 26 formed with the outstanding flanges 27, 28 at their meeting edges which are riveted together, and with the flanges 29, 30 on their vertical edges, by means of which the end structure may be secured to the corner posts 31 of the car frame. The upper sheet 25 is preferably formed with the flange 32 which supports the end of the roof structure of a car, the ridge pole 33 extending over the flange 32 and being secured thereto by means of the bracket member 34. The purlins 35 also rest on the flange 32, the openings between the purlins being closed by a fascia plate 36. Any other suitable means might be employed for securing the end structure to the roof.

75

The lower sheet 26 is formed with a flange 37 which rests upon and is suitably secured to the end sill 38. Preferably the flange 37 has an angular lip 39 which overlaps the inner face of the end sill.

80

The sheets 25, 26 are formed with substantially vertical ribs or corrugations 40, 41. Preferably each plate is formed with two such ribs which align with the corresponding ribs on the other plate, the ribs preferably terminating at the flanges 27, 28 so that they form together, in effect, a pair of

85

posts or load carrying elements extending from substantially the roof down to the floor of the car. In the spaces between the ribs 40, 41 and in the spaces between such ribs and the edges of the sheets are formed transversely extending ribs 42. With the corrugations or ribs so disposed on the end the

90

95

100

105

structure is capable of withstanding all the usual stresses and pressures exerted against the end of a railway car. The structure is very stiff and is capable of carrying a part 5 of the load of the roof.

The car end above described may or may not be provided with a door as desired. In the drawings I have shown a door through the lower sheet metal element 26. In order 10 to nullify, so far as possible, the weakening effect of piercing the sheet with the door opening 43, a flange 44 is struck out from the sheet around the opening. The door 45 is preferably made of sheet metal and is 15 formed on its upper and side margins with the flanges 46, the side flanges having the projecting lips 47 by means of which the door is held in place in the Z-bar guides 48 riveted to the end sheet. The door may 20 be provided with an eyelet 49 which is adapted to be engaged by a hook 50 suspended on a bracket 51 when the door is raised. The Z-bar guides 48 tend to rigidify 25 the sheet around the door opening. The structure of the door 10 and the outstanding flanges 44 on the sheet serve the same function.

In Fig. 8 I have shown a modified construction. Here the two pairs of vertical 30 ribs of the preceding figures are replaced by a single vertical rib or corrugation 52 on each sheet. At each side of the ribs or corrugations 52 are the oblique ribs 53 and the horizontal ribs 54. In other respects 35 the construction shown in this figure may be the same as that shown in Figs. 1 to 7 inclusive.

While I have described my invention in certain preferred embodiments it will be 40 understood that further modifications might be made without departure from my invention.

I claim:

1. A sheet metal end structure for railway cars formed with strengthening ribs pressed out of the metal and running in a substantially horizontal direction, similarly formed strengthening ribs non-continuous with said horizontal ribs which extend 45 in substantially vertical direction, with a flange adapted to support the roof of the car, and with an inturned bottom flange which rests upon the end framework of the car.

2. A sheet metal end structure for railway 50 cars formed with strengthening ribs pressed out of the metal and extending from top to

bottom of the end and spaced apart, and similarly formed transverse ribs non-continuous with said vertical ribs and arranged 55 in the spaces between the first named ribs and between said first named ribs and the side margins of said end.

3. A sheet metal end structure for railway cars comprising upper and lower sheets 60 formed with flanges at their meeting edges which are secured together, with substantially horizontal strengthening ribs pressed out of the metal, and with substantially vertical ribs similarly formed which terminate 70 at said flanges, the vertical ribs of one sheet being in alignment with those of the other.

4. A car end composed of two sections of sheet metal provided with stiffening ribs or corrugations which align at the junction 75 of the sections, the said sections having connecting flanges extending from the protuberant sides of the corrugations.

5. A car end made up of a plurality of joined sections of sheet metal in which are 80 pressed stiffening corrugations which align at the junction of the sections, the said sections having connecting flanges extending from the protuberant sides of the corrugations.

6. In a car end, a sheet metal panel provided with stiffening corrugations and having an attaching flange at the ends of said corrugations.

7. In a sheet metal car end, a plurality of 90 sections secured together at their adjacent edges by means of flanges extending at an angle to the car end, corrugations pressed out of said metal and extending across the flanges to stiffen the end in a direction at an 95 angle to the flanges.

8. In a railway box car having a wood framing, the combination with said framing and the longitudinal sustaining members for the roof; of a sheet metal end 100 structure provided at its lower edge with a horizontally extending flange which stiffens the structure transversely, and at its upper edge with a stiffening flange which serves also to support the longitudinal roof sustaining members, and formed with vertical corrugations which extend substantially from the roof of the car to the floor so as to act as beams rigidifying the sheet metal structure vertically.

IRA S. DOWNING.
